1,944,511

ROAD FORM

John N. Heltzel, Warren, Ohio

Application February 23, 1929. Serial No. 342,263

8 Claims. (Cl. 25—118)

The present invention relates to road forms or rails used in the construction of concrete roads and pavements, and aims to provide a form or rail capable of being used for the construction of slabs of different thicknesses, thereby combining two forms or rails in one for purpose of economy, as well as providing a broad supporting base in either position of the form or rail so that same will be capable of supporting heavy 10 finishing machines.

Another object of the invention is the provision of a form rail having webs of different widths arranged at a right angle with one another, and provided with flanges, in order that either web 15 may be used to define the side of a road under construction, while the other web serves as a broad base to seat on the ground or sub-base, and the flanges permitting the wheels of finishing machines to run on either web when it is in up- 20 right position.

Another object is the provision of a form rail of the character indicated having provisions for receiving stakes in either position of the rail, in order that the rail may be secured in place on the 25 ground or sub-base.

Another object is to provide a novel wedged joint connection to align and secure the abutting ends of two rails together.

With the foregoing and other objects in view, 30 which will be apparent as the description proceeds, the invention resides in the construction and arrangement of parts, as hereinafter described and claimed, it being understood that changes can be made within the scope of what is 35 claimed, without departing from the spirit of the invention.

The invention is illustrated in the accompanying drawings, wherein—

Figure 1 is a perspective view of a fragmentary portion of one of the improved form rails showing the brace and stake.

Fig. 2 is an elevation of the rail and brace.

Fig. 3 is a section on the line 3—3 of Fig. 2.

Fig. 4 is a section on the line 4—4 of Fig. 3.

Fig. 5 is a section corresponding with Fig. 3 showing the rail in its other position to form a slab of a different height.

Figs. 6, 7, 8, 9, 10, 11 and 12 are perspective views of modified constructions embodying the 50 invention.

Fig. 13 is a perspective view illustrating a variation in the stake receiving portions with reference to Fig. 12.

Fig. 14 is a perspective view illustrating another 55 modification.

Fig. 15 is a perspective view illustrating a rail joint device for use with the form rails.

Fig. 16 is a perspective view of a modified form of latch.

Fig. 17 is a perspective view illustrating another 60 rail joint device.

Referring to Figs. 1—5, the form rail is bent from sheet steel of suitable gage, and has the webs 1 arranged at a right angle with one another and provided with the flanges 2 at their opposite 65 edges, with secondary flanges or lips 3 extending from the flanges 2.

The webs 1 are of different widths in order that slabs of different thicknesses may be formed with the same rail. Thus, as seen in Fig. 3, the wider 70 web 1 seats on the ground or sub-base for constructing a slab of less thickness, whereas, as seen in Fig. 5, the narrower web seats on the sub-base while the wider web serves to define the side of the slab of greater thickness. The rail, in its two positions, may thus be conveniently 75 employed for building concrete slabs of different thicknesses, and in each position of the rail the lowermost web serves as a broad base to support the rail on the sub-base. This is a desirable 80 feature when using heavy finishing machines, in order to prevent the depression of the rail into the sub-base.

With either web in upright position, its flange 85 3 provides a tread on which the wheels of the finishing machine may travel. Both webs thus have treads for the finishing machine wheels.

Each rail has one or more braces 4 at suitable longitudinal points thereof. The brace is pressed from sheet metal and has its ends suitably secured to the tread flanges 2. As shown, the ends of the brace 4 overlap the flanges 3 behind same and are welded, riveted, or otherwise secured thereto.

The brace 4 has outwardly pressed pockets 5 95 at right angles to one another and provided with the stake openings 6 through which a stake 7 may be inserted, and the webs 1 have stake openings 8 registering with the corresponding openings 6.

Thus, with the rail in either position the stake 7 100 may be driven vertically downward through the registering openings having their axes vertical. The rail thus has means for accommodating a stake to enter the sub-base, in either position of the rail.

The brace 4 with one pocket 5 corresponds to the brace disclosed in my application Serial No. 263,027, filed March 20, 1928, and the brace 4 has its opposite edge portions pressed or bent 110

inwardly or rearwardly, as seen in Fig. 4, to provide the webs 9 which stiffen the brace.

The webs 9 have slots 10 through which a wedge 11 is slideable to clamp the stake and brace together with the stake passing through either pair of stake openings, the wedge 11 being located between the pockets 5. The wedge 11 has a pin or lug 12 at its smaller end to prevent the removal or loss of the wedge.

10 The brace 4 has transverse stiffening ribs 13 pressed therefrom at the ends of the brace.

Fig. 6 illustrates a tubular form rail which has the webs 1a of different width, and the flanges 2a and 3a, with an inclined bracing web 4a connecting the flanges 3a.

15 A plate 9a is riveted or otherwise secured on the web 4a, and said plate and web have the stake openings 6a to receive the stake 7a in either position of the rail. The plate 9a has an offset 10a through which the wedge 11a is slideable to clamp the stake and rail together, the openings 6a being at the opposite edges of the offset 10a and wedge 11a, so that the wedge may clamp the stake in either opening.

20 Fig. 7 illustrates a brace 4b secured to the treads of the rail and having stake pockets 5b in different transverse planes, while Fig. 8 illustrates separate braces 4c each having a single stake pocket 5c, with said braces in reversed positions.

25 Fig. 9 illustrates a form rail having the tread flanges 2d, without the secondary flanges or lips, and the brace 4d which is secured to the flanges 2d has the curved portion 5d provided with the stake openings 6d, and a wedge 11d is slideable across the inner surface of the portion 5d between the opening 6d. As shown, the wedge has a longitudinal slot 14d receiving holding rivets 15d carried by the portion 5d.

30 Fig. 10 illustrates a variation in that the outstanding portion 5e is of angular form, and the wedge 11e is of similar form to slide within the angle of said portion between the stake openings 6e, and a single holding rivet 15e will be sufficient to extend through the slot 14e for holding the wedge in place for longitudinal sliding movement to clamp the stake.

35 Fig. 11 illustrates a tubular rail similar to that shown in Fig. 6, with an outwardly pressed pocket 5f either integral therewith or secured thereto, and provided with the stake openings 6f and the slots 10f receiving the clamping wedge 11f. The pocket 5f may either be pressed from the web 4f or may be a separate part welded or otherwise secured on said web.

40 Fig. 12 illustrates the inclined web 4g of the tubular rail provided with the inwardly pressed pockets 5g provided with the stake openings 6g, while Fig. 13 shows a single inwardly pressed pocket 5h having the stake openings 6h.

45 Fig. 14 illustrates a form rail of tubular L-cross section, having the portions 3i extending from the flanges 2i parallel with the webs 1i and riveted or otherwise secured together, so that the rail is of hollow angular cross section.

50 The brace 4i has its ends riveted or otherwise secured to the portions 3i and has the stake openings 6i and the side webs 9i, the brace being bent or pressed outwardly. The webs 9i have slots 10i through which the wedge 11i is slideable.

55 Fig. 15 illustrates a rail joint device, including the angular joint plate 16 secured to the webs 1 of the rail and having a projecting portion or tongue 17 to overlap the webs of the companion rail, with the rails in alignment end to end.

60 A pressed sheet metal latch 18 has portions 19 slideable between the flanges 2 and the offset edge portions 20 of the member 16. The outer ends of the portions 20 are rounded, as at 22, so that the latch 18 sliding from one rail into the other will result in the portions 19 moving with a wedging action between the flanges 2 and cam portions 20. This will provide a tight fit between the portions 19 of the latch and the rails. It will be understood that the member 16 of the companion or abutting rail is set back or recessed to receive the outstanding portion 17, and that the latch 18 when projected from one rail moves between the flanges 2 and portions 20 of the companion rail with the wedging action. This will align the rails and hold the abutting ends thereof together.

65 The latch 18 is concaved and has the upwardly or outwardly pressed edge portions or flanges 21, or, as seen in Fig. 16, the latch may be convexed, with the edge portions or flanges 21a bent inwardly or downwardly. The latch may be otherwise deformed to reinforce same.

70 The plate 16 is provided with a stiffening rib or corrugation 23 for purpose of reinforcing or 100 stiffening said plate or member, which is secured permanently to the rail by either riveting or welding, the latch or sliding member 18 being held by the rail for sliding movement.

75 In Fig. 17 there is shown a modified construction of joint device, wherein plates 20b are welded or riveted permanently to the webs 1 of the rail, and the latch plate 18b seats slidably in the corners between the webs 1 and flanges 2 of the rail and has the end portions 19b held slidably 110 between the webs and the offset edge portions of the plates 20b. The plates 20b have the cam portions 22b so that when the latch plate 18b is driven from one rail into the end portion of a registering rail, the plate will be forced with 115 a wedging action between the flanges 2 and portions 22b of the latter rail, thereby alining the rails and holding them together in registration.

80 If the end of the rail into which the latch plate is driven has been bent out of shape or distorted, 120 the rail will be sprung back into proper shape by the wedging action of the latch plate in entering the rail, the end of the rail being either expanded or contracted into shape when the latch plate is forced between the flanges 2 and the cam portions 22b.

85 The structure shown in Fig. 17 is an improvement over the rail latch or joint device shown in my application Serial No. 189,542, filed May 17, 1927.

90 The latch plate 18b functions in either position of the rails, and as shown said plate has the outwardly bent flanges 21b at its side edges and the outstruck rib 24b between said flanges, said flanges and ribs stiffening the plate and being 135 located between the flanges 3 of the rail.

Having thus described the invention, what is claimed as new is:

1. In combination, a form rail having upright and base portions provided with flanges, a bracing member connected to the rail and having flanges adapted to interfit with the flanges of the upright and base portions, and a connecting member of substantially the same configuration as the form rail and having offset edge portions 140 with cam faces adapted to have a wedging action against the flanges of said bracing member when entering the rail.

2. In combination, a form rail of substantially L-shape, a bracing member connected to said rail, 150

and a connecting member having cam faces thereon, said cam faces adapted to have a wedging action with said bracing member when the connecting member enters the rail, said connecting member having a tongue adapted to engage a companion rail.

3. The combination of a form rail having a portion and a flange extending at an angle therefrom, a slip joint member movable into the rail 10 at one end thereof, and a member secured to said portion of the rail adjacent to said flange, said joint member having a portion to move snugly between the flange and second-named member and behind the same, the second-named member 15 having a cam surface for the contact of the joint member for the wedging engagement of the joint member between said flange and second-named member.

4. The combination of a form rail having a portion and a flange extending at an angle therefrom, a slip joint member movable into the rail 20 at one end thereof, and a member secured to said portion of the rail adjacent to said flange and having an offset portion, said joint member 25 having a portion to move snugly between said flange and offset portion and behind said offset portion, said offset portion having a cam surface for the contact of the joint member for the wedg-

ing engagement of said joint member between said flange and offset portion.

5. The combination of a form rail having a base and a web each provided with a flange, a slip joint member movable into the rail between 80 said flanges, and portions secured to said base and web adjacent to the respective flanges, said joint member having portions to move snugly between said portions and flanges.

6. The combination of claim 5 wherein the first-named portions have cam surfaces for the contact of the joint member for the wedging engagement of said joint member between the first-named portions and flanges.

7. The combination of a form rail having a base and a web each provided with a flange, a slip joint member movable into the rail between 85 said flanges, and offset portions secured to said base and web adjacent to the respective flanges, said joint member having portions to move snugly 90 between said offset portions and flanges and behind said offset portions.

8. The combination of claim 7 wherein the offset portions have cam surfaces for the contact of the joint member for the wedging engagement 100 of said joint member between said offset portions and flanges.

JOHN N. HELTZEL.
